CLAIM

The ornamental design for a food container as shown and
described.

DESCRIPTION

FIG. 1 is a top, front, right perspective view of a food
container showing our new design, the food container being
in a closed position.

FIG. 2 is a bottom, rear, left perspective view thereof.

FIG. 3 is right view thereof.

FIG. 4 is a left view thereof.

FIG. 5 is a top view thereof.

FIG. 6 is a front view thereof.

FIG. 7 is a bottom view thereof.

FIG. 8 is a rear view thereof.

FIG. 9 is a top, front, right perspective view of the food
container in an open position.

FIG. 10 is a bottom, rear, left perspective view thereof.

FIG. 11 is right view thereof.

FIG. 12 is a left view thereof.

FIG. 13 is a top view thereof.

FIG. 14 is a front view thereof.

FIG. 15 is a bottom view thereof.

FIG. 16 is a rear view thereof.

FIG. 17 is a top, front, right perspective view of the food
container, shown in a partially open position.

FIG. 18 is a top, front, right perspective view of the food
container, shown in an open position with the flap secured in
the rear.

FIG. 19 is a top, rear, right perspective reference view
thereof, shown in the open position with the flap secured in
the rear; and,

FIG. 20 is a perspective view of the food container shown
in a rolled and secured configuration.

The stippling shown in the figures depicts surface shading.
